UNITED STATES PATENT OFFICE.

CHARLES FISHER, OF CHICAGO, ILLINOIS.

INTERNAL-COMBUSTION ENGINE.

1,232,264.

Specification of Letters Patent.

Patented July 3, 1917.

Application filed July 30, 1912. Serial No. 712,324.

To all whom it may concern:

Be it known that I, CHARLES FISHER, a citizen of the United States, residing at Chicago, in the county of Cook and State of Illinois, have invented a new and useful Improvement in Internal-Combustion Engines, of which the following is a specification.

My invention relates particularly to internal combustion engines; and my primary object is to provide an improved construction and arrangement, whereby the valve mechanism of the engine will operate with smoothness and precision, with a consequent improved operation of the engine as a whole. A further object is to provide for increased durability of the engine and valve mechanism and to obviate danger of the mechanism getting out of order.

The invention is illustrated in the accompanying drawings in the form of a four-cylinder, four-cycle engine of the single-acting type. It will be understood, however, that this embodiment has been selected by way of illustration of a four-cycle engine. The invention, in its broadest aspect, is applicable to other types of engine, such as a two-cycle engine.

In the drawings—

Figure 1 represents a vertical sectional view of an internal combustion engine constructed in accordance with my invention, the section being taken as indicated at line 1 on Fig. 5; Figs. 2 and 2^a represent broken sectional views through the admission and exhaust valves, respectively, the sections being taken as indicated at the lines 2 and 2^a on Fig. 5; Figs. 3 and 3^a represent sections through the admission and exhaust valves at the plane of the third cylinder of the engine, the section being taken as indicated at the lines 3 and 3^a on Fig. 5; Figs. 4 and 4^a represent, respectively, sections through the admission and exhaust valves at the plane of the fourth cylinder, the section being taken as indicated at lines 4 and 4^a on Fig. 5; Fig. 5 a horizontal section taken as indicated at line 5 on Fig. 1; and Fig. 6, a broken sectional view, showing a modification.

In the embodiment illustrated, the invention comprises a series of cylinders A', A², A³, and A⁴; pistons B (one shown) for said cylinders; rotary tubular admission and exhaust valves C, C'; a crank-shaft D connected by connecting rods D' to the pistons;

and a crank-case E which affords a base for the machine and which is surmounted by the cylinders.

In the vertical type of machine here shown, the admission and exhaust valves are horizontally disposed and flank the upper portions of the cylinders, being mounted in cylindrical valve-casings 1 which flank the upper portions of the cylinders and are preferably cast integral therewith. At the front vertical end of the engine is provided a gear-case 2, the body of which is cast integrally with the engine frame and cylinders. This gear-case is provided with a removable plate 3. The rotary valves C and C' have closed ends 4 which project into the gear case 2, and are fitted with gears 5 which are of the same size. Below the gears 5 is mounted, on a pivot 6, a gear or idler 7 of the same size as the gears 5 and meshing therewith. The crank-shaft D is fitted with a pinion 8 which meshes with the gear or idler 7, the pinion 8 having one-half as many teeth as the gears mentioned. From the view shown in Fig. 2, it will be understood that the admission and exhaust valves rotate in the same direction, and at a speed one-half as great as the speed of the crank-shaft.

The other end of the admission valve C is fitted with a nipple or stuffing-box 9 with which is connected an intake-pipe 10 through which the gaseous mixture is drawn from a carbureter 11. The construction is such that the connecting member 9 which is fixed to the rotary valve C can rotate with relation to the admission pipe 10. The exhaust valve C' is provided at its rear end with a union or connecting member 12 which receives the exhaust pipe 13. The member 12 is fixed to and adapted to rotate with the exhaust valve, and the connection is such that the member 12 may rotate with relation to the pipe 13. The engine is shown provided with the usual water-jacket.

At the upper end of each cylinder is a compression chamber 14 and an ignition device 15. Flanking each chamber 14 is an admission port 16 and an exhaust port 17.

The admission valve is provided with a series of admission ports 18^a, 18^b, 18^c, and 18^d. These ports are adapted to register successively with the admission ports 16 of the successive cylinders, and are angularly disposed with relation to each other. Preferably, the admission ports are angularly

separated by spaces of ninety degrees, it being understood that the engine will be so timed that the pistons will operate in succession, so that the torque upon the crank-shaft will be as uniform as possible.

The exhaust valve C' is provided with a series of exhaust ports 19^a, 19^b, 19^c, and 19^d which are adapted to register successively with the exhaust ports 17 of the successive cylinders. The exhaust ports are angularly disposed with relation to each other, being separated by ninety degree angles. The exhaust port corresponding with each cylinder is so disposed that it will pass the exhaust port 17 before the corresponding admission port comes into registration with the admission port 16. This will be understood from Fig. 1.

At the front ends of the valve chambers 1, and within the gear-case 2 are annular bearings 20 adapted to be engaged by the hubs 21 of the gears 5. Washers 22 are shown interposed between the hubs and the bearings. The gear-casing plate 3 is shown equipped with set-screws 23 whose inner points bear against the central portions of the gears 5, so that close joints will be maintained at the bearings 20. In practice, the gear-case 2 will be kept filled with grease, from which source the rotary valves will be lubricated; and the lubricant will, in turn, tend to prevent the passage of gas into the gear-casing.

In Fig. 1, the position of the parts is such that the first cylinder is about to take in a charge. It will be noted that the port 19^a of the exhaust valve C' has already closed the exhaust port 17, while the port 18^a is just coming into registration with the admission port 16. As the piston descends, the charge is drawn into the cylinder, and thereupon the port 18^a passes the port 16, so that both the admission and exhaust ports are closed. On the up-stroke of the piston, the charge is compressed; on the next down-stroke, the firing takes place; and on the second up-stroke the products of combustion are discharged, the exhaust port 19^a in the meantime coming into registration with the exhaust port 17, and then closing after the piston has completed or practically completed its up-stroke. Thus, the valves are again in the position shown in Fig. 1, ready for another cycle. After the piston of the first cylinder has completed its first down-stroke, the admission port 18^b corresponding with the second cylinder comes into registration with the admission port 16 of that cylinder. A similar relation exists between the successive cylinders, and the operation will be understood without further description. Still referring to Fig. 1, it will be understood that the port 18^a will move into full registration with the port 16, or in other words open the port 16 completely, practi-

cally while the piston is at a standstill. The same principle applies to the movement of the exhaust valve C', where the port 19^a moves out of registration with the port 17 during a time when the piston is practically at a standstill, this action occurring, of course, while the crank is traversing the upper arc of the circle in which the crank moves. From the description given, it will be understood that my construction provides for the use of balanced tubular rotary valves actuated by and moving in timed relation with the crank-shaft; also that free ingress and egress to and from the cylinders are provided at the necessary times; that the ingress and egress ports are effectually closed during the compression and working strokes of the piston, extended or substantial bearing surfaces between the rotary valves and the encircling walls of the valve chambers serving at such time to prevent the passage of the gases which are under high pressure; and that the valves are durable, act with precision, and are little liable to derangement. It follows that the operation of the engine is improved and comparatively noiseless and that the life of the engine is increased.

It will be understood, of course, that where the invention is adapted to a two-cycle engine, the gear ratio between the crank-shaft and the rotary valves will be changed, that is, will become the same.

In the modification shown in Fig. 6, the admission valve C^a is employed in lieu of the valve C, and the valve-seat, or sleeve, 1^a, is enlarged at its center, as indicated at x, and connected with the admission pipe x'. The valve C^a is provided with admission-ports x² which register with the annular passage which the enlargement x affords. A similar expedient may be employed at the exhaust valve, if desired, to enable the gases to be discharged from said valve.

The foregoing detailed description has been given for clearness of understanding only, and no undue limitation should be understood therefrom, but the appended claims should be construed as broadly as permissible in view of the prior art.

What I regard as new and desire to secure by Letters Patent is—

1. In an engine of the character set forth, the combination of a plurality of cylinders, a gear-case adjacent an outer cylinder, said gear-case having its inner wall provided with bearings, rotary admission and exhaust valves extending through said bearings into said gear-case, gears in said gear-case secured to said rotary valves, the hubs of said gears abutting against said bearings, an outer plate for the gear-case, means connected with said plate for holding the hubs of said gears against said bearings, pistons in said cylinders, a crank-shaft connected

with said pistons, and gears in said casing connecting said crank-shaft with said first-named gears.

2. In an engine of the character set forth, the combination of a plurality of cylinders, 5 pistons therein, a crank-shaft connected with said pistons, a gear-case cast integrally with one of the outer cylinders and equipped with a removable plate, said gear-case having its 10 inner wall provided with bearings, rotary admission and exhaust valves extending through said bearings into said gear-case,

gears in said gear-case secured to said rotary valves and having hubs abutting against said bearings, adjustable means carried by said plate for holding said hubs against said bearings, and gears in said gear-case serving to transmit motion from the crank-shaft to said first-named gears. 15

CHARLES FISHER.
